UNITED STATES PATENT OFFICE.

FRED CONHAIM AND LOUIS SWENINGSON, OF CLEVELAND, OHIO, ASSIGNEES, BY DIRECT AND MESNE ASSIGNMENTS, TO CONHAIM PATENTS CORPORATION, OF NEW YORK, N. Y., A CORPORATION OF NEW YORK.

FOLDING BED.

Application filed April 14, 1922. Serial No. 552,649.

This invention relates to folding beds, and more especially to beds of the type which are adapted to swing or fold upwardly about a horizontal axis. It is the general purpose and object of the invention to provide a bed of this character with a particularly efficient means for clamping or securing the clothing and the mattress to the mattress support, the said clamping means being preferably operated by the swinging or folding movements of the bed about the horizontal axis. Further and more limited objects of the invention will appear hereinafter and will be accomplished and realized in and through the combinations 15 of elements and in the claims hereto annexed.

The invention disclosed herein is a development of and improvement upon the mattress-clamping means and the mechanism for operating the same shown in the patent to Fred Conhaim No. 1,366,521, issued January 25, 1921.

In the drawings forming part hereof, Fig. 1 represents a longitudinal sectional view 25 of a bed having our invention applied thereto, the particular bed shown herein having its front end mounted in such manner that the bed as a whole may be swung into a closet; Fig. 2 represents a sectional end elevation of the foot portion of the bed, showing our mattress clamp in open or inoperative position; Figs. 3 and 4 are sectional details 30 showing the mattress clamp in its operative position and indicating the positions of the operating parts in connection with mattresses of varying thickness; Fig. 5 is a detail in end elevation and Fig. 6 a detail in side elevation of an operating lever and bracket for the mattress clamp; Fig. 7 is a sectional elevation of the mounting for the front end of the thrust 35 member which operates the swinging foot portion of the bed and the mattress clamp; Figs. 8 and 9 are similar views of modifications of the said mounting; Fig. 10 a detail in plan of the thrust member; Figs. 11, 12 and 40 13 diagrammatic sections illustrating the manner in which the mattress-clamp lever operates the said clamp; and Fig. 14 an elevation of the swinging end of the bed.

The bed shown herein is of the type known to the trade as the "In-A-Dor" bed, being mounted at its head upon a frame which is adapted to swing upon a vertical axis, where- 45 by the bed, when in its elevated position, may be moved into and out of a closet, it not being

intended, however, to limit our invention to beds having such movement.

Describing the various parts by reference characters, 1 denotes one of the side jambs of a doorway having the brackets 2 and 3 to which the bed-carrying frame is pivoted. 60 This frame comprises generally an upper transverse member 4, a lower transverse member 5, suitable vertical members 6 and a frame extending horizontally from the lower transverse member and to which the bed is pivoted. The members 4, 5, and 6, and the said horizontal frame are supported by arms 7 and 8 having vertical trunnions 9 and 10 mounted in the brackets 2 and 3, respectively. 65 The horizontal frame comprises a pair of side members 11 connected at their rear portions by a transverse angle iron brace 12. Each side member 11 is provided with an upwardly extending leg 13 having a foot brace 14 at its upper end. 15 denotes an angular member mounted on each leg 13, each member being connected to the side of the bottom frame 16 of the bed adjacent thereto and near the head thereof and the members 15 being connected by an angle iron 17, springs 18 70 connecting said angle iron and the angle iron 12. The upper corner of each angle member 15 is provided with a boss 19 cooperating with a recess in the foot brace 14, to lock the bed in elevated position while the lower corner of the said member is pivotally connected to the upper end of a link 20 at 20^a, the lower end of said link being pivoted to the front of the lower portion of the leg 13, 75 as indicated at 21.

The swinging head 22 of the bed is connected by one or more springs 23 with the upper transverse member 4.

The parts thus far described are such as are usually employed in the so-called "In-A-Dor" bed.

The foot of the bed is provided with a swinging foot portion comprising legs 24 pivotally connected to the bottom of the bed frame, as indicated at 25, there being a pair 100 of transverse tubular braces 26 connecting said legs.

27 denotes the thrust member generally, the same consisting of a bar of inverted T-section throughout the major portion of 105 its length and a pair of laterally spaced rear extensions of said bar, the bar having at its front end a fork conveniently formed by a

pair of metal straps 28 secured to opposite sides of the web of the member 27 and spread apart at their front ends and each having an aperture in its front end adapted to receive a trunnion 29 on a sleeve 30 slidably mounted upon a bolt 31 and secured in any desired adjusted position thereupon by means of nuts 32, 32^a mounted upon said bolt. This bolt is mounted in the upper and lower flanges 33^a of a channel-shaped bracket 33, the lower flange being provided with a downturned end flange 33^b which is engaged by a similar downturned end flange 34^b on the lower flange 34^a of an angle member having a vertical flange 34. The vertical web and the bottom flange of the channel member and the parts 34 and 34^a of the angle member receive therebetween the transverse brace 12, the upper end of the flange 34 being bent into engagement with the web 33, as indicated at 34^c, and being secured to such web by a bolt 35. The flanges 33^b and 34^b are connected, adjacent to their ends, by bolts 35^a, while the transverse brace 12 is itself braced from the transverse member 5 and the portion 8^a of the bracket 8 by means of a rod 36 having a hook 36^a at its front end extending about the parts 5 and 8^a, with its rear end projecting through the flanges 33^b and 34^b, between the bolts 35^a, and having a nut 36^b applied thereto and bearing against the flange 33^b. The construction comprising the parts 28-36^b inclusive provides means adjustably connecting the front end of the thrust brace 27 to its supporting device and for rigidly mounting such supporting device upon the central portion of the cross brace 12. The rear end of the member 27 has connected to the web thereof a pair of straps 37 similar to the straps 28 and each having its rear end flanged, as shown at 37^a, whereby such end is adapted to bear against the vertical flange 38^a of a cross bar 38, being secured to such flange by bolts 39. This cross bar is adjustably connected to the brace 27 by means of bolts 37^b extending through the vertical web 27 and through slots 37^c in the straps 37. The cross bar is shown as an angle iron, and the brace comprising the parts 27, 28, 37 and 38 is generally T-shaped in plan.

40 denotes a pair of struts interposed between the braces 26, each strut being shown as composed of a front and a rear section connected by bolts 41, each rear section having a lug 42 projecting rearwardly therefrom and each lug carrying a pin 43 to which the rear end of an arm 44 is connected, the front end of each arm being connected to the vertical flange 38^a of the cross member 38 by means of a flange 44^a, formed on the front end of each arm, and one or more bolts 45 securing said flanges to the flange 38^a. Each of the arms 44 is curved intermediate of its ends so as to enable the arms, when the foot portion or legs 24 are folded through the upward movement of the bed about its horizontal pivot,

to assume a position substantially in line with the thrust bar 27, the concavity in each arm 44 receiving the lower cross brace 26—see Figs. 3 and 4. The cross member 38, bar 27, and arms 44 comprise the thrust member referred to hereinbefore.

A pair of brackets, indicated generally at 46, are secured to the foot rail 47 of the mattress frame, each bracket having a pair of downwardly and forwardly extending arms, 7^a each bracket also being provided with a slot adapted to receive the vertical branch of said rail and each bracket being also provided with ears 46^a bearing against said flange, each ear having a slot 46^b by means of which each bracket may be adjustably secured to such rail, as by bolts 48. Each bracket comprises the downwardly and forwardly extending arms 46^c which support at their lower ends a pivot pin 49. At the rear of the foot rail 8^a 47, each bracket is provided with a pair of upwardly extending lugs or ears 46^d which support a pivot bolt 50. Pivoted on each bolt 46 is a saddle consisting of a short cross bar 51 and a pair of upwardly extending ears 51^a 9^a which receive the said bolt. This saddle supports the lower end of one of the curved arms 52 of the mattress clamp. The lower end of each arm extends through its saddle 51, 51^a, beneath the bolt 50 and between the arms 46^c, and is provided at its extreme end with an upwardly and rearwardly inclined portion 52^a, which may be conveniently formed by riveting or otherwise securing to the lower end of such arm a separate piece of metal. The upper end of each arm 52 is so shaped as to engage the front under surface of the top cross bar 24^a of the foot of the bed, the arms 52 being connected by a bar 53.

For the purpose of operating the mattress clamp comprising the parts 51-53 inclusive, through the operation of folding the bed upwardly about its horizontal axis, the following construction is provided:

Each of the curved arms 44 is provided with a pin 44^b which is adapted to enter a vertical slot 54^a in the lower end of each of a pair of lever arms 54, each arm 44 passing between the lower ends of the pair of lever arms 54 operating therewith. Above the slots 54^a, 11^a the arms 54 are deflected outwardly, as shown at 54^b, thus increasing the distance between the upper portions of said arms, the upper portions being spaced apart a sufficient distance to bring them in proximity to the arms 12^a 46^c of their cooperating brackets. The upper end of each arm 54 is generally triangular in shape, each arm having an angular portion 54^c projecting forwardly or toward the head of the bed. A pin 55 connects the front angular portions 54^c of each pair of arms. Links 56 are mounted each at one end on opposite ends of the pins 55 (outside of the arms 54) the other ends of the links being mounted upon the pins 49. Each of the last men- 13^a

tioned pins extends through arcuate slots 54^a in the upper portions of the arms 54, each slot being described about its pin 55 as a center, whereby the lever arms may pivot about the pins 55 as movable or floating centers carried by the movable ends of the links, without interference with the pins 49 which pivotally anchor the opposite ends of said links. 57 denotes a roller mounted between the upper ends of each pair of arms 54, above the pins 55. Each roller is mounted upon a pin 58, the ends of which pins are mounted in arcuate slots 54^a at the upper ends of the arms 54. A helical tension spring 59 connects each pin 49 with a pin 60 which is mounted in the arms 54 above the slots 54^a and tends to hold each lever elevated with each pin 49 at the bottom of the slots 54^a cooperating therewith.

The purpose of the construction embracing the arms 44, arms 54, and their connections with the arms 52, is to enable the mattress clamp to be operated with a minimum strain upon the parts and in the most efficient manner and with a minimum of effort upon the part of the operator. The manner in which this result is accomplished will be explained hereinafter in connection with the diagrammatic views shown in Figs. 11-13.

In applying our clamp-operating means to a bed of the type shown herein, with the bed in its lowered position, the arms 44 are connected to their pivots 43, the nuts on the bolts 37^b being slack. This will enable the folding legs or foot portion to be set to a vertical position when the bed is so lowered. The nuts will then be set up, leaving the trunnion sleeve 30 free on the bolt 31—with the nuts 32 and 32^a at the bottom and the top of said bolt. The bed is then swung upwardly about the pivots 19 after which the nuts will be screwed into engagement with said sleeve. The adjustment which is obtainable by virtue of the connections 27, 37, 37^b and 37^c and by virtue of the mounting of the trunnion sleeve 30 adapts our thrust bar for all ordinary variations occurring in the same types of beds and insures proper positioning of the swinging foot portion.

In the operation of the mattress clamp of the general type shown herein, and more particularly in the Conhaim patent referred to hereinbefore, the maximum force necessary to operate said clamp must be exerted at the beginning of the movement of the same, it being understood, of course, that considerable resistance will be offered to the final movement of the clamp by virtue of its engagement with the bed clothing and the thickness of the mattress. In order to overcome, or at least to greatly minimize, this initial operating effort, the peculiar construction of the lever arms and the peculiar manner of mounting the same are provided.

As the rear end of the bed moves upwardly

about its horizontal pivot, the legs 24 are pulled forwardly about their pivots, causing a corresponding movement of the lower ends of the arms 54 about their pivots 55. By reason of the links 56 and the spring suspension provided by the pins 49 and 60 and the spring 59, the levers comprising the arms 54 and the upper extensions thereof drop, bringing the rollers 57 downwardly, as indicated in Fig. 12, thus causing the said rollers to act nearly at right angles to the inclined surfaces 52^a on the lower ends of their respective arms 52 as the arms 54 pivot about their pins 55. Consequently, the initial movement of the lever arms causes the application of the operating force in the most effective manner, with the result that a minimum effort on the part of the operator is required to institute this movement and a minimum strain is exerted upon the parts which cooperate with the said arms and especially upon the rail 47 which supports the same. This pivoting movement of the lever arms 54 about the movably supported pivot pins 55 causes the upper ends of the lever arms to move rearwardly and downward, as the lower ends of the arms swing forwardly, this downward movement of the lever arms 54 being resisted by the springs 59 which suspend the lever arms from the pins 49. The lever arms swing about their movable pivots 55 until, when the bed is in its upward position, the parts will have assumed the positions shown diagrammatically in Fig. 13, and more fully in Figs. 3 and 4—Fig. 3 showing the positions of the parts where the clamps operate in conjunction with a thick mattress and Fig. 4 the positions of the parts when the clamp operates upon a relatively thin mattress, it being noted that the springs 59 and the slots 54 accommodate this variation in thickness.

The slots 54^a in which the rollers are mounted accommodate variations which may occur in the curvatures and lengths of the arms 52 and in the positions of the cross bars 24^a and enable the upper ends of the arms to rest against such cross bars irrespective of such variations. The thrust due to the operation of the mattress clamp is comparatively light and is taken by the mattress rail 47, dispensing with the necessity for trussing the said rail or the cross rails 26. Furthermore, the operating means for the mattress clamp are light in weight, simple in construction, and comparatively inexpensive of production.

In Figs. 8 and 9 are shown modifications of the mounting for the front end of the thrust member 27. In Fig. 8, the same bracket construction is shown as in Fig. 7 and mounted in the same manner on the cross brace 12, and the corresponding parts designated by the same reference numerals as are employed with Fig. 7. The pin 31^a on which the trunnion sleeve 30 is mounted is un-

threaded and a helical spring 61 interposed between said sleeve and the upper flange 33^a allows the sleeve to adjust itself along the pin as the bed is folded up and to compensate for variations in the dimensions of the cooperating parts.

In Fig. 9 is shown a pin supporting bracket which is particularly adapted for application to the floor as well as to an angle member other than the cross brace 12. The bracket in this case is a single channel casting or forging having a vertical web 62 with upper and lower flanges 62^a and 62^b in which the pin 31^a is mounted, the lower flange being screwed or bolted to the floor, as indicated at 62^c. The bracket is formed with a base flange 62^d additional to the flange 62^b, adapted to rest upon the base flange 63 of an angle iron cross bar, as well as with a bracing rib 62^e; also with end bosses 62^f each supporting a clamping screw 64, said screws being adapted to engage the vertical flange 63^a of said cross bar, which is received within a slot 62^g provided therefor in said bracket.

Having thus described our invention, what we claim is:

1. The combination, with a bed and means supporting the same for movement about a horizontal axis, the swinging end of the bed being provided with a pivoted lower section, of a thrust member pivoted at one end adjacent to such axis and pivotally connected at its opposite end to such lower section, a mattress-clamping arm pivotally supported intermediate of its ends from the swinging end portion of said bed, a lever connected directly to said thrust member and having a portion adapted to engage said mattress-clamping arm, and a fulcrum for said lever movably supported by the swinging end of said bed.

2. The combination, with a bed and means supporting the same for movement about a horizontal axis, the swinging end of the bed being provided with a pivoted lower section, of a thrust member pivoted at one end adjacent to such axis and pivotally connected at its opposite end to such lower section, a mattress-clamping arm pivotally supported intermediate of its ends from the swinging end portion of said bed, a lever adapted to operate upon said arm, means yieldingly supporting said lever for movement in the direction of its length, a laterally offset movably supported fulcrum for said lever, and means connecting the said lever directly to the said thrust member for rocking the said lever about said fulcrum.

3. The combination, with a bed and means supporting the same for movement about a horizontal axis, the swinging end of the bed being provided with a pivoted lower section, of a thrust bar pivoted at one end adjacent to such axis and pivotally connected at its opposite end to such lower section, a mattress

clamping arm pivotally supported intermediate of its ends from the swinging end portion of said bed, a lever having one end operatively connected with said thrust bar, a pivot for said lever intermediate of its ends, one or more links connected with said pivot, the end of said lever which is opposite the thrust-bar connection being adapted to engage the cooperating end of said arm, the said lever having a slot concentric with the said pivot, a pin mounted in said slot and supporting the said link or links, and a spring supporting said lever from said pin.

4. The combination, with a bed and means supporting the same for movement about a horizontal axis, the swinging end of the bed being provided with a pivoted lower section, of a thrust bar pivoted at one end adjacent to such axis, and pivotally connected at its opposite end to such lower section, a mattress-clamping arm pivotally supported intermediate of its ends from a cross member on the swinging portion of said bed, a lever, a pin-and-slot connection between said lever and said thrust bar, said lever having a laterally offset portion and an end opposite said connection adapted to engage the adjacent end of the said arm, a pivot for said lever, and a link connected with said pivot and pivotally connected to the offset portion of said lever.

5. The combination, with a bed and means supporting the same for movement about a horizontal axis, the swinging end of said bed being provided with a lower section movably connected to the upper section, of a thrust member pivoted at one end adjacent to such axis and pivotally connected at its opposite end to the aforesaid lower section, a mattress frame having a cross bar adjacent the swinging end of said bed, a bracket connected to said cross bar, a mattress clamping arm pivotally supported by said bracket, a lever pivoted intermediate of its ends and having one end directly connected to the said thrust member and its opposite end adapted to engage the adjacent end of the said arm, the connection between the lever and the thrust member permitting relative movement between the said member and lever in the direction of the length of the latter.

6. The combination, with a bed and means supporting the same for movement about a horizontal axis, the swinging end of said bed comprising a lower section pivoted to an upper section, of a thrust bar pivotally connected adjacent to the said axis at one end and pivotally connected at its opposite end to said lower section, a mattress-clamping arm pivotally supported intermediate of its ends from said bed, a lever pivoted in operative relation to the operating end of said arm, a lost-motion connection between said lever and said bar, and a movably supported pivot for said lever operating to maintain the line of thrust of the said lever upon the said arm at substantially

right angles to the cooperating surface of said arm.

7. The combination, with a bed and means supporting the same for movement about a horizontal axis, the swinging end of said bed comprising a lower section pivoted to an upper section, of a thrust bar pivotally supported adjacent to the said axis at one end and pivotally connected at its opposite end to said lower section, a mattress-clamping arm pivotally supported intermediate of its ends from said bed, a lever having a slot extending longitudinally thereof, a pivot pin extending through said slot, a yielding connection between said lever and said pin, one end of said lever being slidably connected to said thrust bar and the opposite end of said lever cooperating with the said mattress clamp to rock the latter about its pivot, and a movably supported pivot or fulcrum for said lever.

8. The combination, with a bed and means supporting the same for movement about a horizontal axis, the swinging end of said bed comprising a lower section pivoted to an upper section, of a thrust bar pivotally supported adjacent to the said axis at one end and pivotally connected at its opposite end to said lower section, a mattress clamping arm pivotally supported intermediate of its ends from said bed, a lever having a slot extending longitudinally thereof, a pivot pin extending through said slot, a spring supporting said lever from said pin, one end of said lever being connected to said thrust bar by a pin-and-slot connection and the opposite end of said lever cooperating with the said mattress clamp to rock the latter about its pivot, and a link connected at one end to said pivot pin and at its opposite end to said lever at a point remote from the operating portion of said arm.

9. The combination, with a bed and means supporting the same for movement about a horizontal axis, of a lower section pivotally connected to the upper section of the swinging end of said bed, of a thrust member pivoted at one end adjacent to such axis and connected at its opposite end to the said lower section, a mattress clamp pivoted intermediate of its ends to the swinging portion of said bed, an operating lever adapted to engage the said mattress clamp with one end thereof and connected at its other end directly to said member, the connecting means between the said lever and the said thrust member permitting relative movement between said member and lever in the direction of the length of the lever.

10. The combination, with a bed and means supporting the same for movement about a horizontal axis, the swinging end of said bed comprising a lower section pivotally connected to an upper section, of a thrust bar pivoted at one end adjacent to such axis and having a pair of arms pivotally connected to

such lower section, a mattress clamp comprising a pair of curved arms each pivoted intermediate of its ends, a pair of levers each pivoted intermediate of its ends, and each having an operating portion adapted to engage the adjacent end of one of said curved arms, and a pin-and-slot connection between each of said levers and one of the first mentioned arms.

11. The combination, with a bed and means supporting the same for movement about a horizontal axis, the swinging end of said bed comprising a lower section pivotally connected to an upper section, of a thrust bar pivoted at one end adjacent to such axis and pivotally connected at its opposite end to the lower section, a mattress clamp comprising an arm pivoted intermediate of its ends, a lever pivoted intermediate of its ends and having an operating portion adapted to engage the adjacent end of said arm, a variable connection between said lever and said bar, and means yieldingly supporting the said lever for variable movements about its pivot.

12. The combination, with a bed and means supporting the same for movement about a horizontal axis, the swinging end of the bed being provided with a pivoted lower section, of a thrust bar pivoted at one end adjacent to such axis and pivotally connected at its opposite end to the said section, a bracket supported by the swinging portion of the bed, a mattress-clamping arm supported intermediate of its ends by said bracket, a lever comprising an arm having an angular head, a pin in said angular head, a link connected to said pin, a pin mounted in said bracket and extending through the opposite end of said link and through an arcuate slot in said lever arm, a roller carried by said lever arm and adapted to engage the lower end of the mattress-clamping arm, and a pin-and-slot connection between the lower end of said lever arm and the thrust bar.

13. The combination, with a bed and means supporting the same for movement about a horizontal axis, the swinging end of the bed being provided with a pivoted lower section, of a thrust bar pivoted at one end adjacent to such axis and pivotally connected at its opposite end to the said section, a bracket supported by the swinging portion of the bed, a mattress-clamping arm supported intermediate of its ends by said bracket, a lever comprising a pair of arms each having an angular head, a pin connecting corresponding angles of said arms, a pair of links connected to said pin, a pin mounted in said bracket and extending through the opposite ends of said links and through arcuate slots in said lever arms, a roller mounted in slots in said lever arms and adapted to engage the lower cooperating end of the mattress-clamping arm, a pin-and-slot connection between the lower end of said lever arms and the

thrust bar, a pin mounted in said lever arms below the second pin and a tension spring connecting the two last mentioned pins.

14. The combination, with a bed and means supporting the same for movement about a horizontal axis, the swinging end of said bed comprising a lower section pivoted to an upper section, of a thrust bar pivotally supported adjacent to the said axis and having at its rear end a cross bar adjustably connected therewith, arms carried by said cross bar and pivotally connected to said lower section, a mattress clamp comprising a pair of arms pivoted intermediate of their ends, and levers pivoted intermediate of their ends and each connected at one end to one of the first mentioned arms and arranged to operate upon one of the clamping arms at or adjacent to its opposite end.
15. The combination, with a bed and means supporting the same for movement about a horizontal axis, the swinging end of said bed comprising a lower section pivoted to an upper section, of a thrust bar pivotally supported adjacent to the said axis and having its opposite end provided with a pair of laterally spaced arms each pivotally connected to the said lower section, a pair of mattress clamping arms pivotally supported from a cross member of said bed, a lever for operating each of the last mentioned arms, and a connection between each of the last mentioned levers and one of the first mentioned arms.
16. The combination, with a bed and means supporting the same for movement about a horizontal axis, the swinging end of said bed comprising a lower section pivoted to an upper section, of a thrust bar pivotally supported adjacent to the said axis and having a pair of arms adjustably connected with and constituting an extension of said bar, a piv-

otal connection between each of said arms and the said lower section of the bed, a pair of mattress clamping arms pivotally supported on a cross member of said bed, a pair of levers each pivoted intermediate of its ends for operating a mattress clamping arm, a lost-motion connection between each of said levers and a movable support for the pivotal fulcrum of each lever.

17. The combination, with a bed comprising a mattress frame having end cross bars, and means supporting the same for movement about a horizontal axis, the swinging end of the bed comprising a lower section pivotally supported from an upper section, a bracket carried by the cross bar adjacent to such swinging end, a mattress-clamping arm pivoted to said bracket, a thrust rod pivotally connected at one end to said lower section and pivotally supported at its opposite end adjacent to such axis, and a connection between said rod and said arm.

18. The combination, with a bed comprising a mattress frame having end cross bars, and means supporting the same for movement about a horizontal axis, the swinging end of the bed comprising a lower section pivotally supported from an upper section, a bracket carried by the cross bar adjacent to such swinging end, a mattress-clamping arm pivoted to said bracket, a thrust rod pivotally connected at one end to said lower section and pivotally supported at its opposite end adjacent to such axis, a lever pivoted to said bracket and adapted to operate said arm, and an operating connection between said lever and said thrust rod.

In testimony whereof, we hereunto affix our signatures.

FRED CONHAIM.
LOUIS SWENINGSON.
